PROCESS OF INHIBITING CRACKING IN
RE-FORMING OF HYDROCARBONSRobert E. Burk, Cleveland Heights, Ohio, assignor
to The Standard Oil Company, Cleveland,
Ohio, a corporation of OhioNo Drawing. Application January 14, 1941,
Serial No. 374,370

11 Claims. (Cl. 260—668)

Where hydrocarbons as of normally liquid character are heated with a catalyst for dehydrogenation or aromatization, cracking or breaking of the carbon chains has also occurred to a disturbing extent. In accordance with the present invention such hydrocarbons may be subjected to heat and catalyst for the special action desired, without incurring the disturbance and losses heretofore customary from associated cracking. Other objects and advantages will be apparent in the invention as the description proceeds.

To the accomplishment of the foregoing and related ends, the invention, then, comprises the features hereinafter fully described, and particularly pointed out in the claims, the following description setting forth in detail certain illustrative embodiments of the invention, these being indicative however, of but a few of the various ways in which the principle of the invention may be employed.

The hydrocarbons to be treated may be of character desired, in accordance with particular conveniences of stocks and results in view, and for instance may be hydrocarbons which are normally liquid, or hydrocarbons of at least six carbon atoms, etc. Such hydrocarbon stock is subjected to heat in a range normally productive of wide scale cracking, such as a temperature of 750-1200° F. and the catalyst may be of detail as desired in view of the particular effect contemplated as for instance dehydrogenating catalysts and when the stock has over six carbon atoms any "aromatizing catalyst" by which is understood oxides of the metals of periodic group VI mixed with or deposited on a refractory oxide, such as aluminum, magnesium, thorium, silicon, beryllium, etc., and optionally with the presence of smaller amounts of oxides of copper, etc. The pressure in the heating zone may depend somewhat upon the character of products desired, and for instance where molecular conversion of non-benzoid hydrocarbons to aromatics is required, pressure may be relatively low, as atmospheric up to 200 pounds per square inch, and particularly desirably 50 to 180 pounds. To the heating zone there is also supplied butane hydrocarbon, as butane, or preferably isobutane, or butene in a mixture, the butane supply to be in a ratio of 0.25-4 mol per mol of the hydrocarbon being heated. Generally, a ratio of 1:1 is advantageous. A feed of hydrogen is also supplied to the heating zone, the amount depending somewhat on the total pressure employed, and being for instance 1-6 mol of hydrogen per mol of the hydrocarbon being subjected to the

heating operation. Desirable practice involves about a 3:1 ratio. Flow rates of hydrocarbon feed exclusive of butane may be 0.1-10 v. v. h. A feed ratio of one volume per volume of catalyst per hour is in general satisfactory.

In some cases the off-gases from the catalytic zone may contain hydrocarbons of four carbon atoms and under and also hydrogen such as to be capable of being re-cycled and used in the process for a part or all of the butane and hydrogen requirement.

As an example: A vaporized naphtha from Illinois petroleum is subjected, together with a mixture of isobutane and butane in 1:1 mol ratio, and hydrogen in 3:1 mol ratio, to a temperature of 1025° F. and a pressure of 100 pounds per square inch in a heating chamber in the presence of a 20:80 chromium oxide and aluminum oxide catalyst, the naphtha flow rate being one volume per hour per volume of catalyst. An 80 per cent yield of product showing 84 octane number is obtained. The raw stock had an octane number of 49. In contrast, where operating to a product of the same knock-rating with the conditions the same except that the butane feed is omitted, the yield of the product is much lower, over 20 per cent lower.

Similarly, a narrow naphtha cut including seven carbon atom stock, and a boiling range for instance 172-215° F., is subjected to aromatizing conditions in the presence of an aromatizing catalyst.

By extracting the product with a solvent for the aromatics, as sulphur dioxide, amines, etc., and re-cycling the non-benzoid portion, the percentage yield of aromatics may be still further raised.

Other modes of applying the principle of the invention may be employed, change being made as regards the details described, provided the features stated in any of the following claims, or the equivalent of such, be employed.

I therefore particularly point out and distinctly claim as my invention:

1. Inhibiting cracking in the aromatizing of hydrocarbons, which comprises subjecting a naphtha to a temperature of 750-1200° F. in the presence of an aromatizing catalyst and isobutane supplied in a ratio of 0.25-4 mols of isobutane per mol of naphtha and a greater amount of hydrogen than of isobutane in terms of mols, said hydrogen being supplied in a ratio of 1-6 mols of hydrogen per mol of naphtha.

2. Inhibiting cracking in the aromatizing of hydrocarbons, which comprises subjecting a

naphtha to a temperature of 750-1200° F. in the presence of an aromatizing catalyst and a butane supplied in a ratio of 0.25-4 mols of the butane per mol of naphtha and a greater amount of hydrogen than of butane in terms of mols, said hydrogen being supplied in a ratio of 1-6 mols of hydrogen per mol of naphtha.

3. Inhibiting cracking in the aromatizing of hydrocarbons, which comprises subjecting a non-benzenoid hydrocarbon of at least six carbon atoms to a temperature of 750-1200° F. in the presence of a catalyst of 20 mol per cent chromium oxide and 80 mol per cent aluminum oxide and isobutane supplied in a ratio of 0.25-4 mols of isobutane per mol of said non-benzenoid hydrocarbon and a greater amount of hydrogen than of isobutane in terms of mols, said hydrogen being supplied in a ratio of 1-6 mols of hydrogen per mol of said non-benzenoid hydrocarbon.

4. Inhibiting cracking in the aromatizing of hydrocarbons, which comprises subjecting a non-benzenoid hydrocarbon of at least six carbon atoms to a temperature of 750-1200° F. in the presence of a catalyst of 20 mol per cent chromium oxide and 80 mol per cent aluminum oxide and a butane supplied in a ratio of 0.25-4 mols of the butane per mol of said non-benzenoid hydrocarbon and a greater amount of hydrogen than of butane in terms of mols, said hydrogen being supplied in a ratio of 1-6 mols of hydrogen per mol of said non-benzenoid hydrocarbon.

5. Inhibiting cracking in the re-forming of hydrocarbons, which comprises subjecting a non-benzenoid hydrocarbon of at least six carbon atoms to a temperature of 750-1200° F. in the presence of a catalyst of 20 mol per cent chromium oxide and 80 mol per cent aluminum oxide while re-cycling off-gas providing four carbon atom hydrocarbons supplied in a ratio of 0.25-4 mols of the four carbon atom hydrocarbon per mol of the hydrocarbon of at least six carbon atoms and in the presence of about three times as much hydrogen in terms of mols as four carbon atom hydrocarbons.

6. Inhibiting cracking in the aromatizing of hydrocarbons, which comprises subjecting a non-benzenoid hydrocarbon of at least six carbon atoms to a temperature of 750-1200° F. in the presence of an aromatizing catalyst and isobutane supplied in a ratio of 0.25-4 mols of isobutane per mol of said non-benzenoid hydrocarbon of at least six carbon atoms and also in the presence of hydrogen supplied in amount greater than that of said isobutane in terms of mols, said hydrogen being supplied in a ratio of 1-6 mols of hydrogen per mol of said non-benzenoid hydrocarbon of at least six carbon atoms.

7. Inhibiting cracking in the aromatizing of hydrocarbons, which comprises subjecting a non-benzenoid hydrocarbon of at least six carbon atoms to a temperature of 750-1200° F. in the presence of an aromatizing catalyst and a butane

supplied in a ratio of 0.25-4 mols of the butane per mol of said non-benzenoid hydrocarbon of at least six carbon atoms and also in the presence of hydrogen supplied in amount greater than that of said butane in terms of mols, said hydrogen being supplied in a ratio of 1-6 mols of hydrogen per mol of said non-benzenoid hydrocarbon of at least six carbon atoms.

8. Inhibiting cracking in the aromatizing of hydrocarbons, which comprises subjecting a non-benzenoid hydrocarbon of at least six carbon atoms to heat in a temperature range normally productive of wide scale cracking in the presence of an aromatizing catalyst and isobutane supplied in a ratio of 0.25-4 mols of isobutane per mol of said non-benzenoid hydrocarbon of at least six carbon atoms and also in the presence of hydrogen supplied in amount greater than that of said isobutane in terms of mols, said hydrogen being supplied in a ratio of 1-6 mols of hydrogen per mol of said non-benzenoid hydrocarbon of at least six carbon atoms.

9. Inhibiting cracking in the aromatizing of hydrocarbons, which comprises subjecting a non-benzenoid hydrocarbon of at least six carbon atoms to heat in a temperature range normally productive of wide scale cracking in the presence of an aromatizing catalyst and a butane supplied in a ratio of 0.25-4 mols of the butane per mol of said non-benzenoid hydrocarbon of at least six carbon atoms and also in the presence of hydrogen supplied in amount greater than that of said butane in terms of mols, said hydrogen being supplied in a ratio of 1-6 mols of hydrogen per mol of said non-benzenoid hydrocarbon of at least six carbon atoms.

10. Inhibiting cracking in the re-forming of hydrocarbons, which comprises subjecting a non-benzenoid hydrocarbon of at least six carbon atoms to a temperature of 750-1200° F. in the presence of a dehydrogenating catalyst while re-cycling off-gas providing four carbon atom hydrocarbons supplied in a ratio of 0.25-4 mols of said four carbon atom hydrocarbons per mol of said non-benzenoid hydrocarbon of at least six carbon atoms, and in the presence of about three times as much hydrogen in terms of mols as four carbon atom hydrocarbons.

11. Inhibiting cracking in the re-forming of hydrocarbons, which comprises subjecting a non-benzenoid hydrocarbon of at least six carbon atoms to heat in a temperature range normally productive of wide scale thermal cracking in the presence of a dehydrogenating catalyst while recycling off-gas providing four carbon atom hydrocarbons supplied in a ratio of 0.25-4 mols of said four carbon atom hydrocarbons per mol of said non-benzenoid hydrocarbon of at least six carbon atoms, and in the presence of about three times as much hydrogen in terms of mols as four carbon atom hydrocarbons.

ROBERT E. BURK.
